[57] **CLAIM**

The ornamental design for a hall indicator panel for elevators, as shown and described.

DESCRIPTION

FIG. 1 is a perspective view of a hall indicator panel for elevators showing my new design;

FIG. 2 is a front elevational view thereof;

FIG. 3 is a rear elevational view thereof;

FIG. 4 is a side elevational view taken from the left of FIG. 1, the right side being a mirror image;

FIG. 5 is a top plan view thereof, the bottom plan being a mirror image;

FIG. 6 is a perspective view of a second embodiment of FIG. 1;

FIG. 7 is a front elevational view of FIG. 6;

FIG. 8 is a rear elevational view of FIG. 6;

FIG. 9 is a side elevational view taken from the left of FIG. 6; the right side being a mirror image;

FIG. 10 is a top plan view of FIG. 6, the bottom plan being a mirror image.
